LADY'S STOCKING

Otto F. Smetana, Concord, N. C.

Application June 29, 1949, Serial No. 3,615

Term of patent 14 years

(Cl. D47—7)

To all whom it may concern:

Be it known that I, Otto F. Smetana, a citizen of the United States, residing at Concord, county of Cabarrus, State of North Carolina, have invented a new, original, and ornamental Design for a Lady's Stocking, of which the following is a specification, reference being had to the accompanying drawing, forming a part thereof.

I claim:

The ornamental design for a lady's stocking, substantially as shown.

OTTO F. SMETANA.
